UNITED STATES PATENT OFFICE.

BENJAMIN F. FITCH, OF EVANSTON, ILLINOIS.

GANTRY CRANE.

Application filed September 9, 1920. Serial No. 409,972.

To all whom it may concern:

Be it known that I, BENJAMIN F. FITCH, a citizen of the United States, residing at Evanston, in the county of Cook and State 5 of Illinois, have invented a certain new and useful Improvement in Gantry Cranes, of which the following is a full, clear, and exact description, reference being had to the accompanying drawings.

10 My invention relates to hoisting and transporting mechanism primarily adapted for raising and moving the body of automobile trucks for use in connection with the transfer of freight at terminal stations. My invention is very useful in handling removable truck bodies in a system of hoisting and transporting freight as set forth in my prior Patent No. 1,275,145 issued August 6, 1918.

15 To facilitate the handling of freight by the present invention I provide a raised platform between a truck runway and a freight station and I employ a hoisting and conveying mechanism in the nature of a crane for traveling longitudinally of the platform. 20 The crane embodies features of a one-legged gantry, wherein the upper rail is carried by the outer wall of a building, while the lower rail may be supported near the surface of the platform. The main frame, traveling longitudinally of the platform, overhangs the 25 truck runway and is provided with an overhead trackway on which a supplemental frame traveling transversely of the platform is mounted. Thus I may accomplish lifting 30 and carrying a removable body from a truck positioned on the truck runway to any position on the station platform.

35 A principal feature of my invention is the arrangement of a gantry crane over a station platform extending adjacent a building and longitudinally of a truck runway, the crane on the side adjacent the building being supported on an elevated trackway and on the distant side having a cantilever overhanging the runway. The invention includes also various other characteristics of the construction, which are illustrated in the drawings hereof and hereinafter described in detail. The essential features are summarized in the claims.

40 In the drawings Fig. 1 is a side elevation of a construction embodying the features of my invention and shows a platform intermediate a truck runway and a building; Fig. 45 55 2 is a plan of the crane shown in Fig. 1; Fig.

3 is an end view of a crane having a removable body suspended above and attached to the truck; Fig. 4 is a plan illustrating a station platform and showing the applicability of my invention to existing freight platforms. 60

Designating the parts by the use of reference characters, in Fig. 1, 10 represents a platform intermediate a street or truck runway 11 and the outer wall of a building 12. A trackway, comprising a rail 13, extending longitudinally of the platform 10 together with the rails 14, supported by the wall of a building, constitute supporting means for the main frame of a crane which is adapted to extend outwardly beyond the platform 10 65 and to overhang a portion of the street 11.

A supplemental frame 15 movable longitudinally of the main frame and therefore transversely of the platform 10 is shown as positioned directly over an automobile truck 70 16 and connected with the removable body 17. In general the main frame is adapted to move longitudinally of the platform and the supplemental frame is movable transversely thereof, whereupon removable bodies may be 75 hoisted and transported from a truck to any desired position on the platform or vice versa.

Referring now to Fig. 3, it will be seen that each leg of the crane travels on wheels 80 85 18 which are supported in bearing blocks 19 at the base of the crane. The bearing blocks 19 are carried in brackets 20 and are so arranged that each set of wheels is positioned at the base of a right triangle which 90 has a vertical leg 21, and an hypotenuse 22. These triangular members constitute supporting legs for the main frame, and may comprise fabricated structures of angle bars 95 positioned back to back with lattice strips 23 as braces. The triangular supporting members are connected at the top by an overhead truss on the main frame and at the bottom by connecting bars 24. These bars 24 may be structural members such as angles riveted 100 back to back and secured to gusset plates at the base of the supporting members.

To move the crane longitudinally of the platform, I provide a motor 30 which, as shown in Figs. 1 and 2 may be mounted on 105 the overhead truss and connected thru the worm gearing 31, the beveled gearing 32, the vertical shaft 33, and the gearing 34 to the wheel 18 at the base of the crane.

The main frame of the crane is carried at 110

the top of the triangular supporting members and may comprise a truss having a lower cord 40 which has a portion thereof extending outwardly beyond the platform 10 to overhang the truck runway, together with the upper cords 41 which may be joined to a gusset plate 42 connected with the vertical supporting members 21. As shown in Fig. 3 the overhead trusses are connected by purlins 43 which are spaced at intervals along the upper cord 41 and which may be provided with any suitable roofing material to protect the hoisting mechanism from exposure to weather. Suitable bracing members 44 may be extended between the upper and lower cords to provide a rigid non-flexible truss, while additional reinforcing means may be provided by the oblique members 45 extending from the lower cord to the vertical supporting members.

To support the inner end of the main frame I provide wheels 75 carried in suitable brackets on the transverse end plate 76, and adapted to travel on the rails 14. These rails may be supported on brackets 77, 78, which are rigidly secured to the building 12 by any suitable means. The purpose of inverted rails is to receive the upward thrust and prevent tipping of the crane when the load is supported on that portion of the main frame which overhangs the truck runway. The clearance between the rails 14 and the wheels 75 is only sufficient to prevent any binding action as the crane travels on the platform. Obviously when a loaded body is hoisted and transported from a truck to the platform the bearing strain is changed from the upper set of wheels to the lower set of wheels as soon as the load passes inwardly over the rail 13.

By supporting the inner end of the crane by the wall at an elevated point I leave entirely unobstructed the inner edge of the platform so that I may utilize it for its full width. Doorways through the building wall are thus free from obstruction by gantry legs, and the danger to persons and property which would result from such gantry leg traveling closely across a door opening is avoided. The expense of construction is also reduced by this elevated inner support.

Extending longitudinally of the overhead truss are trackways 50 which, as shown in Fig. 2, are supported by separated plates or brackets 51 which extend inwardly from the lower cord 40. This trackway 50 constitutes a supporting means for a supplemental frame, from which the load is suspended and which is operable independently of the main frame and is adapted to travel transversely of the platform 10. This supplemental frame may comprise a fabricated structure having longitudinal members 55 connected by the end transverse members 56, 57. The supplemental frame is supported on

wheels 58 which are positioned between the end members 56 and 57 and adapted to travel on the trackway 50.

To move the supplemental frame along the overhead trackway I provide a motor 60, 70 which may be secured to the longitudinal beam 55, and may be connected through reduction gearing 61, on the shaft 62, and then through the gearing 63 to the wheels 58. I prefer to extend the shaft 62 longitudinally 75 of the supplemental frame and to employ pinions at each end of the shaft connected with the driving wheels. A mechanical brake (not shown) may be attached to the motor to retard motion of the supplemental frame when the motor is disconnected.

The supplemental frame carries the hoisting mechanism, which comprises a plurality of cables 65 extending from the winding drums 66, over the sheaves 67, to suitable 85 load engaging devices. The winding drums 66 may be operated through the gearing 68 by the motor 69, which is supported on the beams 70 intermediate the ends of the supplemental frame. Suitable control mechanism (not shown) may be provided for regulating the speed of the hoisting cable, while a self-locking device, preferably a worm and worm gear wheel, may be provided within the casing 71, to prevent sudden downward 95 movement of a loaded truck body.

In Fig. 4 I have shown a partial layout of a freight platform provided with my traveling crane having the strut or truck runway 11 and the building 12 adjacent thereto. As shown in this layout sufficient space is provided on the platform for a passageway between rows of bodies for the hand trucking of L. C. L. shipments. The building 12 may be a warehouse or a terminal station, having a floor or interior platform on a level with the outer platform 10, and provided with doorways for trucking either the removable bodies or packages from one platform to another. The outer platform may have provision for teams to handle packages either for incoming or outgoing freight, while the inner platform may be adjacent a set of railroad tracks, whereby a body may be loaded, sealed and transported from one city to another.

Assuming that a truck 16 having a loaded body 17 stops at any position adjacent the platform, wherein there is an opening for a truck, then the main frame travels longitudinally of the platform and the supplemental frame travels transversely thereof, until the load engaging means is positioned directly over the body. After the body is manually engaged and hoisted to clear the truck the main frame travels longitudinally of the platform, while the supplemental frame travels transversely thereof, until the body is over a space where the load is to be deposited. The load is then deposited, in 130

this vacant space, and the crane is transported to a load on the platform which is ready for transportation. This load is then hoisted and conveyed to the truck, whereupon the truck may be immediately dispatched under the direction of a freight dispatcher.

From the foregoing description it will be seen that I have provided a mechanism for hoisting and conveying removable truck bodies; that I have provided a mechanism which is adapted to be installed on existing platforms, which are adjacent buildings such as a terminal station and a truck runway or street, and that I have provided a device which is simple in form and efficient and durable in use.

Having thus described my invention, I claim:

1. The combination with a station platform adapted to support removable automobile bodies, of a building adjacent to one side of the platform, a truck runway adjacent the other side of the platform, a traveling frame movable longitudinally of the platform and supported at its inner end by an overhead trackway adjacent to the wall of the building, legs supporting said frame on a trackway adjacent to the outer edge of the platform, said legs being spaced apart sufficiently to allow the passage of an automobile body, and said frame overhanging said truck runway, hoisting means movable on the frame adapted to travel transversely of the platform and convey a removable automobile body from a truck on the runway onto the platform, there being a doorway through the wall of the building through which the contents of said body may be trucked from the platform to the interior of the building.

2. The combination with a platform, intermediate a street and the supporting wall of a building, removable automobile bodies on the platform, one rail carried by the platform, two rails carried by the wall of the building, a traveling overhead frame, said frame having one side thereof supported on

the rail first mentioned, the other side of the frame being supported by two sets of wheels disposed in planes one above the other and traveling on the wall rails, a trackway carried by said frame and extending beyond one side of the platform, and hoisting mechanism supported by said trackway, whereby a truck body may be raised and transported from the street to the platform, and vice versa.

3. In combination, a freight platform having removable bodies thereon, a truck runway extending along one side of the platform, a building wall adjacent the other side of the platform, two superimposed rails supported by said wall, two sets of wheels disposed one above the other, and positioned intermediate the rails and adapted to travel thereon, a frame having one side thereof connected with said wheels, the other side thereof being supported near the base of the platform, and hoisting means adapted to travel on the frame transversely of the platform for hoisting and conveying a removable body to and from the platform.

4. In combination, a platform adapted to support removable bodies, a main frame traveling thereon, a truck runway adjacent one side of the platform, a wall of a building adjacent the other side thereof, said frame supported intermediately by the platform and at one side by the wall of the building, the other side thereof being adapted to overhang the truck runway, the wall supporting means comprising two superimposed overhead rails, two sets of wheels disposed one above the other and carried by the frame and positioned intermediate said rails, a supplemental frame movable on the main frame and adapted to travel from the wall of the building to a point beyond the intermediate supporting means, and hoisting mechanism depending from the supplemental frame for engaging and raising said bodies.

In testimony whereof, I hereunto affix my signature.

BENJAMIN F. FITCH.
